UNITED STATES PATENT OFFICE.

JAMES W. COLEMAN, OF MONTREAL, QUEBEC, CANADA.

END STIFFENER FOR CARS.

Application filed November 27, 1923. Serial No. 677,265.

To all whom it may concern:

Be it known that I, JAMES W. COLEMAN, a citizen of the United States of America, and resident of the city of Montreal, in the

5 Province of Quebec and Dominion of Canada, have invented certain new and useful Improvements in End Stiffeners for Cars, of which the following is a full, clear, and exact description.

10 This invention relates broadly to car end construction and more particularly to stiffening means therefor, and the primary object of the invention is to provide a novel end construction for cars that will be proof 15 against bulging and separation from the car sides, and also a stiffening means by which existing car ends may be rebuilt or repaired to produce the aforesaid end construction.

A further object is to provide a construction applicable equally to cars in process of 20 building and to cars already built.

25 A still further object is to provide a stiffener so constructed and arranged with relation to the car that the entire space between the inner and outer surfaces of the car end is available for reception of the stiffening means and the inner end surface is free from projections.

30 Another object is to provide an end stiffener of a character suitable for use both on outside metal frame cars of the type generally known as Fowler type cars and to wooden frame cars.

35 Various other objects and advantages may be ascertained from the following description and the accompanying drawings.

40 A considerable number of end stiffening devices for cars have been produced in recent years with a view to preventing bulging of the ends and the separation of the ends and sides, either from shifting of the load due to inertia in stopping and starting the car or to the outward thrust of loads such as grain. Probably the first stiffening 45 device produced took the form of a pair of upright members extending from the under frame to the roof of the car. Various forms of transversely disposed stiffening devices have been proposed, some embodying to 50 greater or lesser extent the features of truss construction. The difficulty of providing a suitable truss has been the limited space at the disposal of designers and the undesirability of encroaching upon the inside 55 measurements of the car and of establishing internal projections at the ends.

According to the present invention a transversely disposed stiffening device of truss construction is provided utilizing to the maximum the available space without 60 encroaching upon the interior of the car or providing inward projections. The stiffening members are of such form that they may be used in any desired spacing and in any 65 location between the floor and roof of a car to correct weakness in existing cars or to impart necessary strength to new construction.

The desired results are obtained by providing transverse trusses having the compression members thereof disposed in the thickness of the car end and the tension members disposed externally of the car, the aforementioned vertical stiffeners serving as 70 queen posts or struts in the trusses. The 75 ends of the trusses are connected to the sides of the car and serve to hold the same against breaking away from the ends. With suitably constructed compression members in the trusses it is found that sufficient camber 80 can be obtained even in the limited thickness of the end sheathing of an outside metal frame car to satisfactorily develop the strength of the tension members. When dealing with a wood frame or other type of 85 double sheathed car, the greater thickness of the ends enables even greater camber to be placed in the compression member of the stiffening truss.

The accompanying drawings illustrate 90 various embodiments or modifications of the invention as adapted for new and old construction of metal frame cars and also for wood frame cars, but it must not be concluded that the forms herein illustrated 95 constitute all the possible variations of the invention, as many others may be made to adapt the invention to particular needs or peculiarities of car construction. It will therefore be understood that these different 100 embodiments of the invention which have been disclosed have been selected from among a number of embodiments merely for the purpose of illustrating the flexibility of the invention, and that the invention must 105 not be considered as in any way confined to these embodiments. In the accompanying drawings:—

Fig. 1 is a partial end elevation of a car end showing the application of stiffeners thereto.

Fig. 2 is a half plan view on an enlarged

scale of one of the stiffeners illustrated in Figure 1.

Fig. 3 is a view similar to Figure 2 illustrating a form of stiffener for and the application of such a stiffener to old construction.

Fig. 4 is a half end elevation of a modified form of stiffener.

Fig. 5 is a half plan view of the stiffener shown in Figure 4.

Figs. 6 and 7 are cross sections on the lines 6—6 and 7—7 of Figures 2 and 5 respectively.

Fig. 8 is an end elevation of the stiffener shown in Figures 4 and 5.

Fig. 9 is a half plan view showing a stiffener as applied to a wood frame car.

Fig. 10 is a side elevation of the tension member anchoring means of Figure 9 substantially on the line 10—10 of Figure 9.

Fig. 11 is a half elevation showing a stiffener having compression and tension members formed integral.

Fig. 12 is a half plan view corresponding to Figure 11.

Referring more particularly to the drawings, 21 designates the corner posts or angles of an outside metal frame and 22 the usual vertical end stiffeners pertaining to metal frame cars. The end sheathing 23 and side sheathing 24 meet within the corner angles 21 and are secured thereto in the well known manner, the details of which are not herein depicted. The end stiffeners 22 are disposed externally of the end sheathing as is well known. The illustration in Figure 1 depicts a car end from the floor line 25 upwardly for a considerable distance but does not extend to the roof.

In one embodiment of this invention which is adapted for application to cars in course of construction and illustrated in Figures 1, 2, 3 and 6, the end stiffeners comprise compression members 26 and tension members 27. The compression members are preferably stamped or upset so as to be channel or U-shaped, in cross section, as clearly shown in Figure 6, but may have any suitable cross section. In the section illustrated, the sides 28 which have a maximum depth equal to the thickness of the end sheathing of the car, are preferably of uniform depth between the uprights 22 and are of gradually decreasing depth between these uprights and the ends of the member, as clearly shown in Figures 2 and 6. One edge of each side is preferably straight and the decrease in width toward the ends is therefore effected by relative inclination of the opposite edges. The inclined edges of the sides and the intermediate straight portion are connected by a web 29 which is therefore cambered or arched. The straight edges of the sides are preferably provided with out-turned flanges 30. The

flanged edges of the sides may, however, be inclined to a lesser extent than the web edges, if the nature of the application will permit. Such a construction is illustrated in Figure 9 and will be referred to later.

The widths of the web and flanges are preferably uniform from end to end of the member but may be otherwise.

At the ends of the member feet 31 are provided disposed preferably at right angles to the flanges 30

and projecting on the web side of the member.

According to this invention the depth of the compression member over flanges and web is equal to the thickness of end sheathing of the car on which it is to be used,

and in outside frame cars the open side of the member is turned outwardly and the flanged edges of the sides 28 are for all practical purposes of necessity straight to conform to the end surface of the car.

When in position, the flanges 30 of the member bear against the upright end stiffeners 22.

The tension member 27 passes outside the uprights 22 and slopes toward the ends of the compression member.

The tension member is preferably a flat plate but may be of any other section and suitably formed at the ends to co-operate with the compression members.

The ends of the tension member are turned over outside the feet of the compression member as at 32.

For new construction the compression and tension members are preferably in contact at their ends and are disposed inside the corner angles 21,

being secured in place by one or more bolts 33 at each end, which bolts may be the usual sheathing attaching bolts of the sides or specially provided bolts.

It will be noted from Figure 2 that in this form of construction the compression and tension members meet a short distance inwardly of their ends and that thereafter the tension member continues in parallelism with the compression member, so that slight bends result in the tension member.

When under load the tendency would be for the tension member to straighten out at these points but by reason of its engagement inside the corner angles 21 this straightening out tendency is resisted by the angle itself, as will be readily seen.

If it is not desired to place entire reliance upon the angles to maintain contact between the compression and tension members and to prevent the straightening out of the bends in the tension member, clamping means—

which will be described in connection with Figure 3—may be resorted to.

The stiffeners are assembled with the frame members of the car as illustrated,

the compression member lying inside the vertical members 22 which form the queen posts or struts of the truss, while the tension members lie outside the vertical members 22.

The stiffeners are employed in any number and spacing desired but prefera-

- bly one is placed quite close to the floor and several more in comparatively closely spaced relation thereabove so as to strongly reinforce the car end in the lower part thereof.
- 6 In the case of a box car especially additional stiffeners may be provided in the upper part of the end and are preferably spaced farther apart than those in the lower part, as illustrated in Figure 1. The end sheathing 23 is applied to fill the spaces between the several stiffeners, the sheathing being rabbeted to receive the flanges 30 of the stiffeners. In this way the stiffeners in reality form part of the end sheathing of the car.
- 10 Toward the ends of the stiffeners where the depth of the compression member is less than the thickness of the sheathing the adjacent edges of the sheathing may be chamfered, as at 34 Figure 6, to avoid the formation 15 of ledges upon which grain or other material would lodge and also to avoid splintering of exposed edges. The maximum depth 20 of the compression member being equal to the thickness of the end sheathing, as already 25 stated, it will be obvious that the inner surface of the car end will be free from projections of any description. When the car end is under load the compression members 30 of the stiffeners, owing to their cambered 30 formation, tend to straighten out and elongate, which tendency is of course resisted by the tension members in the well known manner.
- A slight variation of the structure already 35 described, intended for application to existing cars but in no way excluded from application to new construction, is depicted in Figure 3. This construction differs from that of Figures 1 and 2 only in that the tension member passes outside the corner angles 21 instead of inside these angles. The tension member may be allowed to assume a straight line from the member 22 to the outer corners of the members 21 but is preferably 40 bound in to the inner edges of the members 21 by yokes 35 lying outside the tension members and connected above and below the tension members through the corner posts 21 and sheathing by bolts 36 or the like. This yoke arrangement obviates the necessity of punching the tension member and thereby reducing the section thereof, which reduction would of course necessitate an increase in the width of the member 45 from end to end. The bolts holding the yokes may be those which attach the sheathing or may be special bolts. End and side elevations of a similar yoke are found in Figures 4 and 8 respectively. The operation 50 of this form of stiffener is exactly the same as that already described.
- In Figures 4, 5, 7 and 8 a slightly modified form of structure is shown. The essential difference is that standard structural sections are used for the compression mem-
- ber, but it will be understood that the invention is not confined to the particular standard sections illustrated and that others may be employed. In these figures the compression member, designated 26^a, is composed 70 of a pair of Z-bars 37 disposed inside the corner posts 21 and at their ends abutting the posts. The tension member 27 is similar in all respects to that already described and may be connected to the car and to the compression member in the same way as the member shown in Figure 3. The space between the Z-bars is preferably filled in by a sheathing plank, designated 28. Figure 7, which is suitably bevelled as at 38 to permit of its insertion between the members 37. The Z-bars illustrated are perhaps best adapted for the purpose as they present both inner and outer flanges, thus providing both the necessary web section and the foot 80 flanges for bearing against the members 21 and 22. In this form the effect of the camber in the compression member is lost and reliance is placed upon the tension member for requisite stiffness. It may therefore 85 be necessary in such a construction to employ a slightly heavier tension member than is necessary in the other forms. The Z-bars form absolutely water-tight joints with the adjacent planks when disposed as shown, 90 that is, with inner legs upturned.
- In Figures 9 and 10 is illustrated a modification of the invention suitable for use with wood frame cars. The compression member, designated 26^b, is similar to the member of Figure 2 except that on account of the greater end thickness of the car end much greater camber is possible. The depth 100 of the sides 28 is, however, limited in the central part of the member to the thickness 105 of the inner sheathing 23^b so as to avoid cutting into the intermediate end uprights 39. The central part of the compression member is flush with the inner surface of the car and the member slopes at its ends 110 into abutting relation with the corner posts 21^b and with the outer sheathing 40. In order to stiffen the upright 39 a structural member such as the Z-bar 22^b is attached 115 against the outer surface thereof if not already present. The tension member 27^b passes outside the upright strut member 22^b and around the corner posts. The ends of 120 the compression and tension members are connected together by the bolt 33^b, the corner posts 21^b being in compression between the ends of the members. The yoke 35 previously described is preferably adopted to bind the tension member against the end of 125 the car. Owing to the different nature of wood frame car construction as compared with outside metal frame construction the attaching bolts 36^b of this yoke are extended along the inner surface of the car side and are anchored by means of bolts 130

41 passing through an extension 42 of the tension member end which lies along the outer surface of the car side. A filler 43 such as the belt rail of the car is necessarily 5 interposed. The central part of the compression member replaces the inner sheathing 23^b which has been removed to give place to the stiffener but on account of the greater inclination of the compression member 10 in a wood frame car, as compared with that obtained in an outside frame type of car, which leaves recesses of considerable size, it is necessary to replace the inner sheathing over the inclined portions of the 15 compression member. This is most conveniently accomplished by bolting the necessary sheathing to the compression member, a filler 44 being supplied between the compression member and sheathing.

20 The stiffener is applied in wood car construction by removing a necessary amount of inner and outer sheathing and inserting the compression member in the car. The compression member is held to the uprights 25 39 by bolts 45 which also hold the vertical stiffeners 22^b. The tension member is then applied and bolted to the compression member through the corner posts of the car and the other fastenings applied. The inner 30 sheathing is replaced over the inclined ends of the compression member and bolted in place and the outer sheathing finally replaced. When under load the compression member thrusts outwardly against the corner posts and this thrust is resisted by the tension member overlying the corner posts, with the result that the car end is held 35 rigidly against bulging. The yoke 35 holds the tension member against slackening and its 40 attachment bolts form with the extremity 42 of the tension member a closed rigid loop within which the wooden car members are merely in compression. While the compression member disclosed for use in wooden 45 cars is of the pressed type, it will be understood that ordinary structural sections may be substituted.

The stiffener trusses heretofore described have all been composed of separate compression and tension members but it is not necessary that the members should be separate, unless it is desired to employ standard structural shapes for the compression member. In Figures 11 and 12 there is shown a 50 press stiffener truss having integral compression and tension members 46 and 47 respectively. This result is obtained, as will be readily seen, by forming the compression and tension members side by side from a 55 single plate and then shearing through the plate along two longitudinally disposed lines (which terminate short of the ends) to separate the members except at the ends and enable them to be positioned in different

planes to receive a queen post or strut between them. For various reasons it is preferred to employ two compression members with a common tension member between them as shown, but the arrangement may be reversed, that is, two tension members with a compression member between them. In either case the duplicated member should not be regarded as two members but rather as a single member divided. This type of stiffener is available for either new construction or repair work on any type of car to which stiffeners are applicable. 65 70 75

In all forms of the device the end stiffeners in addition to holding the ends from bulging form rigid connections between the 80 sides of the car and hold the sides against separation from the ends. In all forms the compression member is located in the thickness of the car end, thereby utilizing to the maximum the space available between the 85 inner surface of the car end and the outer face of the striking plate. As the strength of a section varies as the square of its depth it will be readily seen that utilization of the thickness of the end sheathing enables a 90 much stronger truss to be provided than if the truss was disposed entirely externally of the sheathing. The construction is simple, easily applied and inexpensive, and in one 95 form or another is applicable to any type of car either during construction or as a repair. If the exposure of the compression members at the inner surface of the car is undesirable in cold or damp climates on account of frosting or sweating, the difficulty may be overcome by the provision of a thin supplementary sheathing disposed either externally or internally. The method of yoke fastening disclosed in Figures 9 and 10 is not limited to use with wood frame cars but may be applied equally well to outside metal frame 100 105 cars, if desired.

The term "sheathing" as used in the following claims is to be considered as applying equally to the sheathing of a metal frame 110 car and the inner sheathing or lining of a wood frame car.

Reinforcing trusses as herein described may if desired be disposed vertically with consequent horizontal disposition of the 115 strut members.

Having thus described my invention, what I claim is:

1. An end stiffener for cars comprising a compression member to be disposed in the 120 thickness of the car end, and a tension member to be disposed externally of a car.
2. An end stiffener for cars comprising a compression member and a tension member, the compression member including a cambered web and sides tapering toward the 125 ends, the edges of said sides opposite the web being straight and presented to the ten-

sion member, the tension member being connected at its ends to the ends of the compression member.

3. An end stiffener for cars comprising a compression member to be disposed in the thickness of a car end sheathing, and a tension member to be disposed externally of a car and to be spaced in its central part from the compression member by intermediate end 10 uprights of the car.

4. An end stiffener for cars comprising compression and tension members, the compression member being of substantially channel shape and disposed with its concave 15 surface adjacent the tension member and including a cambered web and sides tapering toward the ends.

5. An end stiffener for cars comprising compression and tension members, the compression member being of substantially channel shape and disposed with its concave 20 surface adjacent the tension member and including a cambered web and sides tapering toward the ends, feet on the ends of the compression member turned away from the tension member, the ends of the tension member being turned parallel with and connected to said feet.

6. An end stiffener comprising a compression member and a tension member, the compression member including a web remote 30 from the tension member, sides approaching the tension member, and flanges on the edges of the sides adjacent the tension member, the tension member being turned at its ends over the ends of the compression member and secured to the compression member.

7. An end stiffener comprising a compression member and a tension member, the compression member including web and side 40 portions, the latter being flanged adjacent the tension member, and the tension member being turned at its ends over the ends of the compression member and secured to the compression member.

8. An end stiffener comprising a compression member and a tension member, the compression member including a cambered web remote from the tension member, sides on 50 said web approaching the tension member and out-turned flanges on the edges of the sides adjacent the tension member, the tension member being turned at its ends over the ends of the compression member and secured to the compression member.

9. An end stiffener comprising a compression member and a tension member, the compression member including a cambered web remote from the tension member, sides on 60 said web approaching the tension member and straight in the edges adjacent the tension member and out-turned flanges at the edges of the sides adjacent the tension member, and the tension member being turned

at its ends over the ends of the compression 65 and secured to the compression member.

10. An end stiffener comprising, in combination with the end uprights of a car, a truss including a compression member disposed inwardly of said uprights, and a tension member disposed outwardly of the uprights and connected at its ends to the ends of the compression member, the uprights serving as the strut of the truss.

11. An end stiffener comprising, in combination with the corner and intermediate end uprights of a car, a truss including a compression member disposed inwardly of the intermediate uprights, and a tension member disposed outwardly of the intermediate uprights, the ends of said compression and tension members being connected to one another and to the corner uprights, the intermediate uprights serving as the strut of the truss.

12. An end stiffener comprising, in combination with the intermediate end uprights of a car, a compression member disposed inwardly of the uprights and including a web spaced from the uprights, sides on said web 90 extending to the uprights, and flanges on said sides bearing on the uprights, and a tension member disposed outwardly of the uprights and connected at its ends to the ends of the compression member.

13. An end stiffener comprising, in combination with the corner and intermediate end uprights of a car, a compression member disposed inwardly of the intermediate uprights including connected web and side 100 portions, the latter being flanged at the edges remote from the web portion to present bearing surfaces for engagement with the intermediate uprights, and a tension member disposed outwardly of the intermediate uprights and connected at its ends to the ends of the compression member and to the corner uprights.

14. An end stiffener comprising, in combination with the corner and intermediate end uprights of a car, a compression member disposed inwardly of the intermediate uprights including sides disposed normal to the intermediate uprights, flanges on the sides bearing on the intermediate uprights, said sides being tapered from the intermediate uprights to the ends and a cambered web connecting the sides and inclining outwardly toward the ends, and a tension member disposed outwardly of and bearing against the intermediate uprights, the ends of the compression and tension members being connected to one another and to the corner uprights and the intermediate uprights cooperating with the members to form a truss.

15. An end stiffener comprising a compression member and a tension member connected at their ends, and a strut between said

- members being a part of the car to which the stiffener is applied.
16. An end stiffener comprising a compression member to be disposed in the thickness 5 of a car end, a tension member connected at its ends to the ends of the compression member, and a strut between said members being a part of the car to which the stiffener is applied.
17. An end stiffener comprising a compression member to be disposed in the thickness 10 of the end sheathing of a car, a tension member connected at its ends to the ends of the compression member, and a strut between 15 said members being a part of the car to which the stiffener is applied.
18. An end stiffener comprising a compression member including laterally directed feet at the ends, a tension member connected 20 at its ends to said feet and further connected to the compression member at points between the feet thereof.
19. An end stiffener comprising separate 25 compression and tension members connected together at their extremities, and means connecting the members between their extremities.
20. An end stiffener comprising separate 30 compression and tension members connected together at their extremities, and means connecting the members between their extremities, said means embracing the tension member and connecting the same to the compression member at points between their extremities.
21. An end stiffener comprising a compression member and a tension member connected together at their extremities, yokes overlying 35 the tension member between the extremities of the member and fastenings for said yoke securing the members together.
22. Car end construction including uprights, a plurality of separate transverse 40 stiffening trusses engaging said uprights and end sheathing disposed intermediate said trusses and forming with the trusses a complete end closure.
23. Car end construction including uprights, sheathing connected to said uprights forming an incomplete end closure, a trans- 45 verse stiffening truss engaging said uprights and forming with the sheathing a complete end closure. 50
24. Car end construction including uprights, sheathing connected to said uprights 55 and presenting a transverse opening, and a transverse stiffening truss engaging the uprights and in part occupying the said opening and forming with the sheathing a complete end closure. 60
25. Car end construction including corner and intermediate uprights, sheathing connected inside said uprights, and a transverse stiffening truss connected at its ends to the corner uprights and having the compression 65 member thereof disposed inside the intermediate uprights and in the plane of the sheathing, and the tension member disposed outwardly of the intermediate uprights, the said intermediate uprights serving as truss 70 struts.
26. In car end construction, including corner and intermediate uprights and sheathing, a transverse stiffening truss, the compression member of which is equal in depth to the 75 thickness of the sheathing.
27. Car end construction including a series of connected trusses, and sheathing interposed between said trusses and forming with the trusses a complete end closure. 80
28. Car end construction comprising a series of trusses connected together at their ends and arranged with the compression members thereof in spaced relation, sheathing interposed between the compression members of said trusses and forming with such compression members a complete end closure, and strut members disposed at right angles to the trusses between compression and tension members thereof. 85
- In witness whereof, I have hereunto set my hand. 90

JAMES W. COLEMAN.
